United States Patent Office.

CHARLES K. MYERS, OF PEKIN, ILLINOIS, ASSIGNOR, FOR ONE-HALF, TO
PETER WEYHRICH, OF SAME PLACE.

Letters Patent No. 97,955, dated December 14, 1869.

IMPROVEMENT IN TIGHTENING AND GUIDING BELTS.

The Schedule referred to in these Letters Patent and making part of the same.

To all whom it may concern:

Be it known that I, CHARLES K. MYERS, of the city of Pekin, in the county of Tazewell, and in the State of Illinois, have invented a Device for Tightening and Directing Belts for Machinery; and do hereby declare that the following is a full, clear, and exact description thereof, reference being had to the annexed drawings, making a part of this specification, in which like letters of reference refer to like parts, and in which—

Figure 1 represents a perspective view.

Figure 2, an elevation of belt-tightener and "shoe."

Figure 3, section of same.

Figure 4, perspective view, showing bed of shoe and pulley-arm.

Figure 5, a side elevation of tightener.

Figure 6, perspective view of auxiliary belt-director.

Figure 7, elevation of same.

Figure 8, plan of same.

Figure 9, "shoe" of "tightener."

This is an improvement in the manner of tightening and guiding or controlling the running of belts for machinery, by a simple device.

The bearings of pulleys, for directing the belt, are made adjustable at requisite angles for this purpose.

The drawings illustrate the device as applied to "Haines' Illinois harvester."

A is the front of the main frame of the machine.

B, the back-board of platform, running parallel with the former.

C is the draper-frame, carrying roller at its upper end, with a pulley on the axle of the same, L.

D is the slotted arm, carrying the tightener-pulley E.

This arm is adjustable at various heights, by means of the slot g g, fig. 4, cut in the vertical face of the frame A, deep enough merely to steady it; another slot, f f, running transversely of this slot, and deep enough to embed the "shoe" f f, and form a slot in which it can be adjusted to the right or left; the face of the shoe projecting somewhat above the level of the vertical slot g g.

The pulley E is attached, by a horizontal spindle, to the upper part of the slotted tightener D.

F is the shoe or adjuster of the "tightener-arm" D, which forms the bed or bearing against which the tightener-arm is bolted and adjusted.

The bolt d passes through the hole in the frame behind, and successively through the slot e, (in the "shoe" F,) and the slot a in the arm D.

The curved face of the shoe projects, as before stated, above the level of the slot g g, by which it will be seen that any shifting of the shoe F, either to

the right or to the left, behind the arm D, will incline the latter, and the axis of the pulley E, more or less from a line joining the frame at a right angle, by which the belt is adjusted to run evenly on defective pulleys, at a distance, as at L, which have become displaced by wear of their axles, &c., or other impairment, causing the belt to run off the impaired pulley.

The bolt d, at the same time, is used to readjust the pulley E, as a tightener on the belt K, by sliding the arm D under its nut, when loosened.

The pulley E is secured on the tightener-arm by a left-hand nut or bolt, or equivalent fastening, b, and washer.

G is a rectangular iron plate, with vertical slot, n, cut or cast in part of its length, and an oblique slot, l, of similar size, through which passes the end of the pulley-rod of pulley H, (as in Haines' harvester.)

This plate is adjustable in a slot cut vertically in the back part of the frame A, and is adjustable therein by means of a bolt in the slot n.

A mortise or oblong horizontal slot, k, fig. 7, admits the end of the pulley-rod through the frame A, which rod passes on through the slot l.

Now, the slot k, in the frame allows of a horizontal motion of the end of the pulley-rod, so that a blow on the top of the plate G forces the end of the rod to the right hand; contrarily, a blow on the under edge of the plate will cause the oblique slot l to force the end of the rod in the opposite direction, thus causing the pulley H, on the rod, to assume a different angle to suit the belt.

This pulley H being situated on the "joint-rod," in this drawing, or example, will illustrate the use of the plate G, and its effect on said rod and pulley. The belt passes beneath the latter, under the draper-pulley L, around it, and back again beneath the pulley D, or tightener, and thence around the crank-pulley M, or belt-driver.

What I claim as my invention, is—

1. The combination of the slotted "shoe" F, and its bed f f, with the slotted arm D, pulley E, left-hand nut b, adjusting-bolt d, and slot g g, in frame A.

2. Adjusting-plate G, with its bolt-slot n, and pulley-rod slot l, in combination with the mortise k k, pulley H, and its rod o, all substantially as described, and for the purposes set forth.

In testimony that I claim the foregoing, I have hereunto set my hand, this 18th day of October, A. D. 1869.

CHARLES K. MYERS.
